DESIGN FOR A SMOKING PIPE

Henry Allen Browne, Chicago, Ill.

Application April 16, 1942, Serial No. 106,583

Term of patent 3½ years

To all whom it may concern:

Be it known that I, Henry Allen Browne, a citizen of the United States, residing at Chicago, in the county of Cook and State of Illinois, have invented a new, original, and ornamental Design for a Smoking Pipe, of which the following is a specification, reference being had to the accompanying drawing forming part thereof.

I claim:

The ornamental design for a smoking pipe, as shown.

HENRY ALLEN BROWNE.
